UNITED STATES PATENT OFFICE.

JOSEPH C. UPTON, OF PELZER, SOUTH CAROLINA.

LOOM.

Application filed February 4, 1922. Serial No. 534,080.

To all whom it may concern:

Be it known that I, JOSEPH C. UPTON, a citizen of the United States, residing at Pelzer, in the county of Anderson and State 5 of South Carolina, have invented certain new and useful Improvements in Looms, of which the following is a specification.

My invention relates to improvements in looms, and has particular reference to looms 10 of the type known as "needle" looms.

An important object of the invention is to provide a needle loom so constructed that it may be employed to weave wide fabrics, such as fabric having the width of a yard 15 or more, this machine being adapted to operate at a greater rate of speed than the ordinary shuttle loom.

A further object of the invention is to provide means to place the filling in the 20 warp, in pairs of strands, lock each pair to one edge of the fabric and twist the threads in each pair throughout their entire length.

A further object of the invention is to provide a machine of the above mentioned 25 character, which is wholly automatic in operation.

Other objects and advantages of the invention will be apparent during the course of the following description.

30 In the accompanying drawings, forming a part of this specification, and in which like numerals are employed to designate like parts throughout the same,

Fig. 1 is a vertical section taken on line 35 1—1 of Fig. 2,

Fig. 2 is a plan view of a machine embodying my invention,

Fig. 3 is a longitudinal section taken on line 3—3 of Fig. 1,

40 Fig. 4 is an enlarged side elevation of the twisting mechanism and associated elements, parts being shown in section,

Fig. 5 is a detail section taken on line 5—5 of Fig. 4,

45 Fig. 6 is an enlarged longitudinal section through the shuttle taken on line 5—5 of Fig. 4,

Fig. 7 is an enlarged central longitudinal section through the twisting mechanism, 50 showing a portion of the needle associated therewith,

Fig. 8 is a transverse section taken on line 8—8 of Fig. 7,

55 Fig. 9 is a partly diagrammatic view, showing the starting position of the needle,

Fig. 10 is a similar view, showing the needle approaching the twister,

Fig. 11 is a similar view, with the needle at the twister, which has engaged the looped thread,

60 Fig. 12 is a similar view, showing the needle receding from the twister, still holding the strands,

Fig. 13 is a similar view with the needle at the edge of the fabric, the twisting operation being completed, and,

Fig. 14 is a similar view, the twisted strands being released from the twister, and banked upon the fabric.

70 In the drawings wherein for the purpose of illustration is shown a preferred embodiment of my invention, the numeral 10 designates the frame ends or castings of the loom, which may be of any well known or preferred construction.

Rotatably mounted 75 within the lower rear portion of the frame is a drum 11, carrying the warp threads 12, which pass upwardly over a rear guide roller 13, supported by arms 14.

The warp threads are divided in two leaves, as well 80 known, and pass through the heddles 15, carried by the saddles 16. The warp thread then extends forwardly through the reed or comb 17 and the fabric 18 passes about

a take up roller 19, suitably mounted upon 85 the frame. The fabric then passes about a guide roller 20 and is wound upon a roller 21, the roll 22 of the fabric contacting with the fabric passing about the take up roller 19 and is driven thereby.

The roller 21 is 90 carried by vertically movable bars 23, having teeth 24, engaged by gears 25, mounted upon a shaft 26. This shaft is turned in one direction by a spiral spring 27, and the arrangement is such that the bars 23 tend to move the roller 21 upwardly, but of course the bars move downwardly as the size of the roll 22 of the fabric increases.

The numeral 28, Figs. 1, 2 and 3, designates a horizontally arranged main drive 100 shaft, extending longitudinally of the frame work. This main drive shaft may receive

its power from a motor or the like. The main drive shaft is provided with cranks 29, near the sides of the frame, and these 105 cranks are connected with links or pitmens

39, pivoted at 31 to vertically swinging arms 32, having the comb 17 secured upon their upper ends. By this construction the comb 110 remains substantially stationary upon the

left side of the needle, until the needle has had sufficient time to make its entire travel forwardly and rearwardly through the leaves of the warp. Any other suitable means may be employed to move the comb, in proper timed order.

The roller 11 is driven at a suitable speed by a worm wheel 40, driven by a worm 40', carried by a shaft 41', provided with a bevel gear 42'. This bevel gear is driven by a bevel gear 43', rigidly mounted upon a counter shaft 44'.

A bevel gear 45' engages the opposite side of the bevel gear 43', and is rigid upon a shaft 46', having a worm 47', engaging a worm wheel 48'. This worm wheel drives a train of gears 49', which operates the feed roller 19.

The counter shaft 44' is driven by a gear 50', engaging a gear 51', rigid upon the shaft 28, as shown.

The counter shaft 44' is provided with a central crank 48, having pivotal connection with a pitman 49, extending forwardly for pivotal connection within a disk 50. This disk has a segmental slot 50a, receiving a pin 51a, carried by the pitman 49, and this provides for a proper lost motion. The disk 50 is rigidly mounted upon a counter shaft 51, suitably journaled in the frame, and carrying disks 52 near its ends. These disks 52 have links 53, extending upwardly for connection with the saddles 16. The saddles are supported by links 54, pivoted upon an upper horizontal shaft 56, supported by brackets 57. It is obvious that the heddles are caused to move in opposite directions to shift the leaves of the warp. Any suitable means may be employed to properly shift the heddles, and the invention is in no sense restricted to the means shown.

The numeral 58 designates a table or support, arranged upon a pedestal 59 or the like, one end of this table being anchored to the side frame of the loom proper. A housing 60 is formed upon the upper surface of the table 58, and preferably cast integral therewith. This housing extends transversely of the loom, with one end thereof arranged near and in cooperative relation to the comb 17. The housing 60 has a longitudinal bore 61, which is preferably cylindrical, and this bore receives a needle supporting sleeve or carrier 62. The carrier is held against turning movement by a depending stud or trunnion 63, operating in a longitudinal slot 64, which leads into a lower chamber 65. The stud or trunnion 63 carries a transverse bar 66, rigidly secured thereto, and this bar has a longitudinal groove 67 upon its lower face, slidably receiving a stud or trunnion 68, rigidly mounted upon a disk 69. This disk 69 is mounted to rotate within the chamber 65, and is rigidly secured upon a vertical shaft

70, driven by a bevelled gear 71. The bevelled gear 71 receives its rotation from the bevelled gear 72, driven by a counter-shaft 73, and this counter-shaft is rotated by a bevelled gear 74. The bevelled gear 74 is engaged by a bevelled gear 75, receiving its rotation from the main driving shaft 28, as clearly shown in Fig. 2. From the foregoing description it will be seen that the rotation of the disk 69 will impart a reciprocatory movement to the sleeve or carrier 62.

The numeral 76 designates a needle, the rear end of which is held within the sleeve or carrier 62, to be reciprocated by the sleeve. The forward portion of the needle projects beyond the sleeve and is disposed in concentric relation to the bore 61. The forward exposed portion of the needle is of a length whereby the needle is adapted to completely traverse the leaves of the warp, the disk 65 having a suitable diameter to cause the needle to reciprocate sufficiently so that the free end of the needle is moved to and beyond the opposite edges of the warp. In Fig. 7, the numeral 77 designates the front end of the needle, which may be slightly curved, as shown, and provides a curved shoulder 78, serving as an eye, for holding of the filling.

Attention being now called more particularly to Figs. 7 and 8, it will be seen that the numeral 79 designates a cylindrical casing, formed upon or carried by the front end of the needle. This casing is adapted to move rearwardly into the bore 61, with the needle. The casing 79 is positioned transversely of the needle, at a right angle to the filling extending longitudinally of the needle. This casing is cylindrical, as shown in Fig. 8, and receives a rotatable twisting element 80, in the form of a rotor, having teeth or blades 81, which pass successively the discharge ends of compressed air ports 82, formed circumferentially within the casing 79. The ports 82 are in connection with a longitudinal port 83, extending through the needle, and in suitable communication with a suitable source of compressed air. No preferred means are shown for supplying the compressed air from the pressure tank to the longitudinal port 83, as it is obvious that many devices can be used for such purposes. It will be seen that the compressed air discharging from the ports 82 impinges upon the teeth or blades 81, causing the rotor 80 to revolve. The opposite sides of the casing 79 have large circular openings 84, through which the filling passes. The rotor 81 is provided with a radial opening 85, adapted for registration with a radial opening 86, in the casing 79. The opening 84 registers with the opening 86 to permit of the escape of the filling, at the end of the twisting operation. The numeral 87 designates a radial finger or

catch element, arranged within the rotor 80, which is annular, with its bore in registration with the openings 84. The finger 87 is adapted to engage with the lower strand 88 of the filling, the other strand 89 being so positioned that the finger 87 will not engage therewith but will travel around it. It is obvious that the finger should pass between the two strands, engaging one and carrying it around the other strand, thereby completing the twisting with the two strands, throughout their entire length within the leaves of the warp.

Attention being now called more particularly to Figs. 4 and 7, it will be seen that I have provided a twisting device including a rotatable tubular head 88', horizontally arranged within a stationary bearing 89'. This head is located in longitudinal alignment with the needle, so that the loop carried by the needle may be engaged by the twisting means carried by the rotatable head to be described. A plug or bearing 89^a is preferably screw threaded within the rear end of the tubular head 88', and has longitudinal openings to slidably receive rods 90. These rods are connected with a disk 92 splined upon a stud shaft 93, integral with the plug 89^a. This disk is capable of sliding longitudinally of the stub shaft but cannot turn thereon. Pivottally connected with the forward ends of the rods 90 are links 94, extending forwardly and connected with L-shaped fingers 95, pivoted at 96 in the head 97. The L-shaped fingers 95 have their longitudinal portions operating within slots 98. These longitudinal portions are provided at their free ends with outwardly projecting lateral extensions 99, to engage with the filling as shown.

The numeral 100 designates a shuttle casing, which is annular, and stationary. This casing is supported by radial arms 101, mounted upon a bracket 102. The shuttle casing is arranged near the twisting mechanism, and is so positioned that the needle when passing to the twisting mechanism travels through openings 103 in the shuttle casing. A shuttle disk 104 is rotatable within the shuttle casing, and is rigidly mounted upon a shaft 105, journaled through a bearing 106. The shuttle casing and shuttle disk are disposed parallel to the leaves of the warp. The shuttle disk 104 has provided upon its periphery an extension or tooth 107, adapted to engage behind a shuttle 108, and to cause the same to travel in the direction of the arrow, within a shuttle casing. The specific construction of the shuttle will be given hereinafter.

The shaft 105 carries a bevelled gear 109, engaged and driven by a bevelled gear 110 mounted upon a counter-shaft 111. This shaft 111 has a bevelled gear 112 secured to its opposite ends engaging a gear 113,

rigidly mounted upon the main driving shaft 28. The shaft 105, Fig. 4, has a gear 114 rigidly mounted thereon, engaging a smaller gear 115, mounted upon the rotatable tubular head 88. It is desired that 70 the twisting device be driven at a greater rate of speed than the shuttle, and for this purpose the gear 115 is made smaller than the gear 114. The disk 92 carries upon its periphery a roller 116 pivoted thereto, and this roller operates within a cam groove 117 in a disk 118, rigidly mounted upon the shaft 105. The function of this construction is to shift the disk 92 rearwardly, at the proper time, when the roller 116 enters the laterally offset portion 117' of the cam groove, and this movement of the disk will swing the free ends of the fingers 95 inwardly, for releasing the loop in the twisted filling, and also to provide a free passage for 85 the shuttle, the several parts being of course properly timed in operation.

The construction of the shuttle is shown in detail in Fig. 6. This shuttle embodies a front casing 119, having a tapered nose 120. 90 A rear casing 121 is detachably connected with the front casing 119, by means of a screw threaded engagement 122. The numeral 123 designates a spool or bobbin, the 95 yarn passing from this bobbin to the exterior of the shuttle through an opening 124. A disk 125 is rotatably mounted within the forward end of the rear casing 121, preferably by means of ball bearings, and this disk has a friction recess 127, engaging an extension or trunnion 128 formed upon the end of the bobbin, the opposite end of the bobbin having a trunnion 129, rotatable in a recess 130. The disk 125 constitutes one element 100 of a clutch, and a ring 131 constitutes the 105 coacting element of the clutch. This ring 131 carries a packing strip 132, to engage with the disk 125. The ring 131 is rigidly mounted upon a disk 132, formed upon a shaft 134, which is square in cross section. A coil spring 135 surrounds the shaft 134 and is connected with the disk 132 and the shaft 134, and opposes the rotation of the disk 132 in one direction upon the extension 133. The shaft 134 slides within a square 110 opening in a guide 135, rigidly mounted upon the rear end of the casing 121, but cannot turn therein. A compressible coil spring 136 surrounds a shaft 137 carried by the shaft 134, and serves to move the shaft 134 forwardly, to cause the ring 131 to have proper frictional engagement with the disk 125. The tension of the spring 137 is regulated by an adjustable bearing 138. It is 115 thus seen that if the yarn is pulled from the bobbin, in excess, the bobbin will be rotated, and the rotation will to some extent be imparted to the disk 25, by virtue of the slipping friction joint between the trunnion 128 and the disk. This will cause the disk to 120 125 130

turn which will rotate the disk 132 and place the spring 135 under tension. Should a slack now occur in the yarn passing through the bobbin 123, the spring 135 will automatically return to its normal state, rotating the disk 132, and disk 125 in a reverse direction, thereby reversing the rotation of the bobbin 123, and automatically takes up the slack in the yarn fed from the bobbin.

10 The operation of the device is as follows: With the comb 17 upon the left side of the needle 77, the needle is moved from the starting position, Fig. 9, forwardly through the leaves of the warp toward the twisting device, as shown in Fig. 10. When the needle moves into proximity to the twisting device, Fig. 11, the fingers 99, Fig. 7, catch the loop in the yarn and the twisting commences. The twisting operation continues while the 15 needle is traveling to the right, Fig. 12, and continues until the needle has returned to the starting position, Fig. 13. During the operation of the twisting fingers 99, the rotatable twisting element or rotor 80 has also 20 served to twist the yarn, throughout its entire length. At about the time that the needle has been returned to the starting position, and the twisting operation completed, the bobbin 119 is passed through the loop held by the fingers 99, and this end of the 25 yarn is anchored to the fabric. Subsequent to this operation, the cam groove 117 shifts the roller 116 and its disk 92 to the left, and the fingers 99 will swing inwardly, 30 releasing the loop, Fig. 14. The comb is now shifted forwardly to pack the twisted strand and returned to the starting position before the needle again advances. The 35 comb does not move forwardly until the needle has completed its cycle of operation, and the heddles 15 operate in a similar manner.

It is to be understood that the form of 40 my invention herewith shown and described is to be taken as a preferred example of the same, and that various changes in the shape, size and arrangement of parts may be resorted to without departing from the spirit 45 of my invention or the scope of the subjoined claims.

Having thus described my invention, I claim:

1. In a loom of the character described, 50 means for supporting and advancing the warp leaves, heddles for shifting the leaves, a needle for carrying a plural strand filling yarn transversely between the leaves, means for twisting the strands of each filling together between the warp leaves, means for locking each filling to one edge of the fabric, and a reed to beat up the twisted filling.

2. In a loom of the character described, 55 means for supporting and advancing the warp leaves, heddles for shifting the leaves,

a needle for carrying a plural strand filling yarn transversely between the leaves, means for twisting the strands of each filling together throughout substantially their entire length between the warp leaves and a 60 reed to beat up the twisted filling.

3. In a loom of the character described, 65 means for supporting and advancing the leaves of the warp, heddles for shifting the leaves, a needle to carry the filling yarn transversely between the leaves, twisting mechanism to engage the filling near the end of the needle for twisting the strands of the filling and forming an eye, means to cause the twisting mechanism to release the filling, a shuttle to travel through the eye and lock the filling to one edge of the fabric, and separate twisting means acting upon the yarn of the filling to further twist the 70 same.

4. In a loom of the character described, 75 means for supporting and advancing the leaves of the warp, heddles for shifting the leaves, a needle to carry a plural strand filling yarn transversely between the leaves, a shuttle movable through the eye of the filling near the end of the needle, twisting mechanism engaging the strands of the filling embodying a rotor carried by the needle, 80 means to drive the rotor, and a reed for beating up the twisted filling.

5. In a loom of the character described, 85 means for supporting and advancing the leaves of the warp, heddles for shifting the leaves, a needle to carry a plural strand filling yarn transversely between the leaves, a shuttle arranged to travel through the eye of the filling near the end of the needle, a casing connected with the needle and bodily movable therewith, a rotor mounted 90 within the casing and having means to engage one strand of the filling to twist the same about the other strand, and means for supplying compressed air to the casing for driving the rotor.

6. In a loom of the character described, 95 means for supporting and advancing the leaves of the warp, heddles for shifting the leaves, a needle to carry a plural strand filling yarn transversely between the leaves, a shuttle arranged to travel through the eye of the filling near the end of the needle, mechanism for twisting the strands of the filling together and movable bodily longitudinally of the strands, and a reed to beat up the twisted filling.

7. In a loom of the character described, 100 means for supporting and advancing the leaves of the warp, a circular shuttle casing arranged near one edge of the leaves and having transverse openings, a shuttle disk rotatable within the shuttle casing and having 105 a radial projection, a shuttle rotatable within the shuttle casing and driven by the projection, a needle movable transverse-

ly between the leaves of the warp and adapted to carry a plural strand filling through the openings in the shuttle casing, means for twisting the strands of the filling together, heddles for shifting the leaves of the warp, and means for beating up the twisted filling.

8. In a loom of the character described, as a subcombination, a rotatable head,

twisting fingers pivoted to the head and 10 bodily rotatable therewith, automatic means to turn the fingers upon their pivots, a needle to advance the filling in proximity to the fingers, and means for passing a shuttle through the filling.

In testimony whereof I affix my signature.

JOSEPH C. UPTON.
